CLAIM

The ornamental design for a flexible video endoscope, as shown and described.

DESCRIPTION

FIG. 1 is a front perspective view of a flexible video endoscope according to the present invention.

FIG. 2 is a front view of the flexible video endoscope of FIG. 1.

FIG. 3 is a rear view of the flexible video endoscope of FIG. 1.

FIG. 4 is a left side view of the flexible video endoscope of FIG. 1.

FIG. 5 is a right side view of the flexible video endoscope of FIG. 1.

FIG. 6 is a top view of the flexible video endoscope of FIG. 1; and,

FIG. 7 is a bottom view of the flexible video endoscope of FIG. 1.

The flexible video endoscope is shown with a symbolic break in its length. The appearance of any portion of the article between the break lines forms no part of the claimed design.

The broken lines depict portions of the flexible video endoscope and form no part of the claimed design.

1 Claim, 7 Drawing Sheets
